UNITED STATES PATENT OFFICE.

LOUIS J. REMMELE, OF NEWARK, NEW JERSEY.

TABLE FOR FILLING ROTARY BROOMS.

SPECIFICATION forming part of Letters Patent No. 743,328, dated November 3, 1903.

Application filed November 7, 1902. Serial No. 130,396. (No model.)

To all whom it may concern:

Be it known that I, LOUIS J. REMMELE, a citizen of the United States, residing at Newark, in the county of Essex and State of New Jersey, have invented and produced a new and original Improvement in Tables for Filling Rotary Brooms; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to the manufacture or refilling of rotary brushes or brooms such as are used for snow-sweeping by street-railways and for similar purposes. Heretofore it has been common to insert in said brushes the reeds forming the sweeping part thereof by hand, which has been a very slow and tedious operation, it requiring one man about a day to fill a single broom.

The objects of my invention are to enable such filling to be done mechanically and to provide for this purpose a suitable table or apparatus, to obtain a simple and easily-operated device, to secure a great saving of time and labor, to obtain uniformity in the brushes, and to secure other advantages and results, some of which will be hereinafter referred to in connection with the description of the working parts.

The invention consists in the improved table for filling rotary brooms and in the arrangements and combinations of parts of the same, all substantially as will be hereinafter set forth and finally embraced in the clauses of the claim.

Referring to the accompanying drawings, in which like letters of reference indicate corresponding parts in each of the several figures, Figure 1 is a plan of my improved table with reeds arranged thereon at full length as in the preliminary steps of filling a broom-section. Fig. 2 is a side elevation of the same, and Fig. 3 is an end view. Fig. 4 shows in cross-section as upon line α , Fig. 1, the table in extended position. Fig. 5 is a similar sectional view after the table has been closed or folded. Fig. 6 is a sectional view taken longitudinally of the table as upon line

γ , Fig. 4. Fig. 7 shows in perspective a certain toothed holding-rod hereinafter described. Fig. 8 is a detail perspective view illustrating certain tipping guide-pins, the same being shown in lowered position. Fig. 9 is an end and Fig. 10 a front elevation of the said guide-pins in standing position, and Fig. 11 shows in perspective the supporting-bar for said guide-pins.

In said drawings, 2 indicates the top of my improved table, which is horizontally supported at any suitable height upon legs 3 and cross-braces 4, adapted to secure rigidity and firmness. Said table-top is divided longitudinally of the table into two portions 5 6, each of which is preferably formed of stout planks or boards and the two being hinged together, as at 7 7. One of the two portions, 7 0 as 5, is fastened securely upon the table-supports, while the other, 6, is left free and can thus be tipped over into superposed position upon the stationary part 5. Each leaf has at its outer edge a raised flange or border-piece 7 5 8, and upon the top of this flange is a wider strip 9 of heavy sheet metal. Said wider strip 9 of sheet metal has transverse slots 10, adapted to receive bolts 11, extending downward through the said strip 9, flange 8, and 8 0 the table-top and each having at its lower end a nut, with a wrench 111 or equivalent turning means permanently carried thereby. By loosening said bolts 11, therefore, the metal strip 9 can be slid to project inward 8 5 from the flanges 8, as shown in Figs. 1 and 4, or the said metal strips can be slid outward to coincide at their inner edges with the inner edges of said flanges, as will be understood.

The table 2 is of somewhat greater length 9 0 than the brushes whose segments are to be filled one at a time on said table, and in operation the reeds or ratan strips 12, which are to form the sweeping part of the broom, are first laid transversely of the table, the metal strips 9 being slid outward to facilitate this step. When a sufficient number of reeds have been so arranged upon the table, the metal strips 9 are slid in over the ends thereof and hold them in place, as shown in Figs. 1, 3, 4, and 5 of the drawings more especially. A section-frame 14 of my improved broom, shown in my copending application, Serial No. 130,397, filed November 7, 1902, and to

which reference is made for more complete description, is then laid longitudinally of the table upon the reeds arranged thereon and is secured at its opposite ends outside said 5 reeds. Briefly, said brush-section frame consists of transverse plates 15, arranged at suitable intervals upon connecting-rods 16, 17, and 18, projecting at their ends beyond the endmost plates and threaded to receive nuts. 10 When placed upon the table, the side rods 18 18 are removed, and of the remaining two rods, one, as 17, is adapted upon the removal of its end nut to be inserted in adjustable brackets 19 upon the table-top and by means 15 of which the said broom-section frame is held in place. Said adjustable brackets 19 are located upon the stationary portion of the table-top adjacent to its edge next to the swinging leaf, and each comprises a piece of sheet metal 20 bent at right angles and having in its foot or horizontal portion 20 a slot 200 to receive a bolt 22, extending into the table-top, and in its vertical portion 21 a laterally-opening slot 211 to receive the end of the rod 17. Preferably the table-top 2 is recessed at its upper 25 surface along its middle and on both sides of the line of hinging of the stationary and swinging sections, so as to receive the frame of the broom-section being filled without the 30 latter projecting upward too much for the reeds to lie flat on the table, all as shown in Figs. 4 and 5 more especially. After said brush-section frame has been locked in place, as described, with its transverse plates separating the reeds into groups, as shown in Figs. 35 1 and 6; an auxiliary holding-strip 212 is applied to the swinging section of the table. Said auxiliary strip has pins or teeth 213 arranged at distances apart equal to the distances 40 between the plates 15 of the broom-section frame, and in applying said holding-strip the said pins are inserted into the divisions between the groups of reeds close to said plates of the frame 14. The entire holding-strip is then drawn outward a distance 45 upon the swinging section 6 of the table to where said table-section is provided with a longitudinal series of sockets 214 for the said pins to sink into. The extremities of the 50 holding-strip project beyond the ends of the table and are locked to fastening-bolts 23 thereon, as by nuts 24.

The stationary section 5 of the table has also a fixed row of pins 25, spaced as are the 55 holding-strip-pins 213 and plates 15 of the brush-section frame 14 and which serve to originally divide the reeds in groups as they are arranged on the table. The swinging section 6 of the table-top is next turned over into 60 a superposed position by means of hand-levers 26, transversely mounted thereon near its ends and projecting from its free or outer edge, as shown in Figs. 4, 5, and 6, and this bends or doubles the reeds around the rods 16, 17 of the 65 broom-section frame into proper relative position thereon, as shown in Fig. 5. The side rods or stays 18, 18 of the said broom-section frame

are then pushed endwise into place in the perforated plates 15, and afterward the metal strip 9 of the swinging section of the table is 70 released from the ends of the reeds and said swinging section of the table returned to its original position, leaving the broom-section properly filled upon the stationary table-section. 75

Preferably to avoid even the slight danger of any of the reeds riding up upon the edges of the section frame-plates 15 as they are bent I provide a bar 27, adapted to lie along the hinge-joint of the two table-sections and 80 being journaled at its opposite rounded ends 28 in supports 29, projecting from the stationary table-leaf and having flattened portions adapted to be clamped to the table-top by the same bolts 22 which hold the brackets 19. 85 The said bar 27 has pins or teeth 30, spaced like the broom-section frame-plates 15, and when the bar lies normally edgewise said pins project horizontally toward the swinging table-section out of the way of placing reeds on the 90 table, as shown in Fig. 4. When, however, the said bar is turned a quarter-turn preliminary to closing or folding the table, said pins are brought to stand upright against the edges of the plates 15, as shown in Fig. 5. 95

Obviously various modifications and substitutions of equivalents may be made in my device as described without departing from the spirit and scope of the invention, and I do not wish to be limited by the positive descriptive terms employed except as the state of the art may require. 100

Having thus described the invention, what I claim as new is—

1. A table for filling rotary broom-sections, having a top with a swinging leaf adapted to be opened outwardly, or to be folded into superposed position, and means for securing reeds and a broom-section frame, respectively, to said table-top. 105

2. A table for bending or doubling broom-reeds, having a top with two sections hinged one to the other and adapted to be folded together or opened to lie in the same plane, and means for securing reeds in transverse position upon said sections. 110

3. A table for filling rotary broom-sections, having a top with two hinged sections adapted to be extended to lie in the same plane or to be brought into superposed position, means 115 for supporting said sections, and means for holding reeds and the broom-section, respectively, in place thereon.

4. A table for filling brooms, comprising two sections, one stationary and the other hinged thereto and adapted to be extended to lie in the same plane or to be closed into superposed position, means at the opposite outer margins of said sections for holding a transverse series of reeds upon the table, and means at the opposite ends of the said fixed section and adjacent to its inner edge for holding a broom-section frame. 125

5. A table for filling rotary broom-sections,

comprising a suitable supporting-frame, a top composed of two sections one of which is fixed to said frame and the other free, said leaves being hinged together, means for securing a 5 series of reeds transversely on said leaves, and means for holding a broom-section frame longitudinally.

6. In a table for filling rotary broom-sections, a top comprising two hinged sections, 10 each having upon its free margin a raised flange and upon said flange an inwardly-projecting strip, one of said strips being laterally adjustable upon its flange, means for securing a broom-section frame longitudinally 15 upon the table intermediate of said outer margins of the section and means for folding said sections together.

7. In a table for filling rotary broom-sections, hinged leaves upon which the reeds are 20 adapted to be spread, the opposite outer margins of said leaves having stops for the ends of said reeds, and the adjacent inner margins being recessed and forming a central groove, and means for securing a broom-section 25 frame in said groove.

8. In a table for filling rotary broom-sections, the combination with supporting means, of hinged leaves one stationary and the other swinging, and said leaves being recessed at 30 their adjacent margins to form a central groove, brackets mounted in said groove upon opposite ends of the stationary leaf and adapted to receive a broom-section frame, and means upon the outer portion of said leaves 35 for securing reeds in transverse position thereon.

9. In a table for filling rotary broom-sections, two hinged leaves having at their opposite outer margins means for securing a transverse 40 series of reeds in place thereon and having near their inner hinged edges means for longitudinally supporting a broom-section frame, a series of vertical reed-spacing pins arranged on one of said leaves adjacent to its 45 inner edge, and means for supporting and for swinging said leaves.

10. In a table for filling rotary broom-sections, the combination of two hinged leaves having at their outer marginal portions means 50 for securing the ends of a transverse series of reeds and having adjacent to their line of hinging means for holding a broom-section

frame in longitudinal position, one of said leaves being fixed and the other free, a series of spacing-pins on the fixed leaf, the free leaf having a correspondingly-placed series of sockets, a holding-strip having pins or teeth adapted to enter said sockets, and means for locking the ends of said strip to the leaf. 55

11. In a table for filling rotary broom-sections, the combination with hinged leaves adapted to receive a transverse series of reeds and means adjacent to the line of hinging of said leaves for supporting in longitudinal position a broom-section frame having transverse plates, of a guiding-strip pivotally supported at its ends upon one of said leaves and having a series of teeth or pins spaced to correspond to the said section frame-plates and adapted to project upward from the table and 60 lie against the edges of said plates. 70

12. A table for filling brooms, having a top comprising sections adapted to be folded together or opened to lie in the same plane, and means for securing reeds and a broom-section, 75 respectively, upon said top.

13. A table for bending reeds, having a top comprising sections adapted to be extended to lie in the same plane and receive the reeds and to be brought into folded relation to bend 80 said reeds, and means for securing the reeds to said top.

14. In a table for filling brooms, a top comprising sections adapted to be folded together or opened apart to lie in the same plane, said 85 sections providing a recess between the adjacent edges of their upper surfaces, and means for securing a broom-frame in said recess parallel to the line of folding of the sections.

15. In a table for filling brooms, the combination of a table-top comprising a stationary section and a swinging section hinged together, means for securing a broom-frame longitudinally upon said stationary section adjacent to its inner edge, and means for 95 holding reeds transversely in position on said table-top.

In testimony that I claim the foregoing I have hereunto set my hand this 3d day of November, 1902.

LOUIS J. REMMELE.
